UNITED STATES PATENT OFFICE

WALTER D. TEAGUE, OF FOREST HILLS, NEW YORK, ASSIGNOR TO CORNING GLASS WORKS, OF CORNING, NEW YORK, A CORPORATION OF NEW YORK

DESIGN FOR A COMBINED COFFEE MAKER AND SERVER

Application filed December 21, 1932. Serial No. 46,543. Term of patent 14 years.

To all whom it may concern:

Be it known that I, WALTER D. TEAGUE, a citizen of the United States, residing at Forest Hills, in the county of Queens and State of New York, have invented a new, original, and ornamental Design for a Combined Coffee Maker and Server, of which the following is a specification, reference being had to the accompanying drawing, forming part thereof.

The figure is a perspective view of the combined coffee maker and server showing my new design.

I claim:

The ornamental design for a combined coffee maker and server as shown.

WALTER D. TEAGUE.
